UNITED STATES PATENT OFFICE.

CYRUS H. LOUTREL, OF SOUTH ORANGE, NEW JERSEY, ASSIGNOR TO THE NATIONAL LOCK WASHER COMPANY, OF NEWARK, NEW JERSEY, A CORPORATION OF NEW JERSEY.

NUT-LOCK.

1,065,149.

Specification of Letters Patent. Patented June 17, 1913.

Application filed December 27, 1912. Serial No. 738,880.

To all whom it may concern:

Be it known that I, CYRUS H. LOUTREL, a citizen of the United States, residing at South Orange, county of Essex, State of New Jersey, have invented certain new and useful Improvements in Nut-Locks; and I do declare the following to be a full, clear, and exact description of the invention, such as will enable others skilled in the art to 10 which it appertains to make and use the same.

My invention has reference to nut locks which are cut from a cylindrical coil of suitable metal and subsequently tempered.

15 The object of my invention is to greatly stiffen nut locks of this sort and to increase the resistance afforded by the nut lock against the clamping elements, further objects being to enable the nut lock to seat 20 more firmly against said elements as the latter are contracted and to cause the nut lock to bite with greater force into the surfaces of these elements.

With these ends in view, my invention 25 consists in the peculiar and novel constructions hereinafter fully described and then particularly pointed out in the claims which conclude this description.

In the accompanying drawing Figure 1 30 is what I would term a front elevation of my improved nut lock, looking toward the severed ends—Fig 2 a rear elevation of such nut lock—Fig. 3 a side elevation of the nut lock—Fig. 4 a front elevation of the nut 35 lock showing the same partially clamped—Fig. 5 a rear elevation of the nut lock partially clamped—Fig. 6 a side elevation of such nut lock partially clamped, and Fig. 7 a plan view of the nut lock.

40 Similar numerals of reference denote like parts in the several figures of the drawing.

After the nut locks have been cut from the cylindrical coil, they are in the form of plain spiral segments and are substantially 45 the commercial nut locks that have been in use for many years. In carrying out my improvement I subject these spiral segments to the action of a press, a drop hammer or other suitable agent, whereby certain trans- 50 verse portions of the segment including the side faces and the edges are gradually curved in a lateral direction out of the line of the spiral to form concavo-convex compressible spring portions. In some instances 55 the end portions of the nut lock are undis- turbed, while the intermediate portions, re-

mote from the ends, are curved gradually and laterally out of the line of the spiral; and in instances where great resistance must be afforded by the nut locks both the end 60 and intermediate portions are gradually curved laterally out of the line of the spiral. As such curved portions are straightened out by the action of the clamping elements, said portions will exert a greatly increased 65 resistance against such elements. By gradually curving the intermediate portions of the nut lock laterally out of the line of the spiral and in alternate directions, the nut lock is made to seat with great stability 70 between the clamping elements, and such lock is thereby greatly stiffened because during the clamping action these curved portions will act as additional spring portions which, when straightened out by such clamping, 75 will largely increase the resistance of the nut lock against said elements. I prefer to curve the intermediate portions of the nut lock gradually and laterally in reverse directions out of the line of the spiral, and in the drawing 80 these curves on one side of the nut lock are designated by the numerals 3, 4, while the corresponding curves on the other side of the nut lock are designated by the numerals 5, 6. When the extreme ends 1, 2, of the 85 nut lock are curved in the manner above described, these curved portions 3, 4, 5, and 6, are within the planes of the terminals of said ends as clearly shown at Figs. 1, 2, and 3.

Referring to Figs. 4, 5, and 6, the surface 90 against which the nut lock is clamped is designated by the numeral 7, while the numeral 8 designates the nut which is driven on the bolt 9 against such nut lock. In these Figs. 4, 5, and 6, in which is illustrated my im- 95 proved nut lock constructed for maximum resistance to the clamping action, said nut lock is shown partially clamped between the elements 7 and 8, and it will be noted that there are three seating points on both faces 100 of the nut lock, namely, the curved portions 1, 3, and 4, and the curved portions 2, 5, and 6, while between these curved portions parts are gradually curved laterally out of the line 105 of the spiral that are designated respectively by the numerals 10, 11, on one face of the nut lock, and by the numerals 12, and 13, on the other face of such lock. These curved portions of the nut lock all extend trans- 110 versely of the segment and include the side faces and the edges, and, extending as they do laterally out of the line of the spiral of

the nut lock in opposite directions, form concavo-convex compressible spring portions which must be straightened out before the nut lock is finally clamped between the 5 elements 7 and 8, and therefore these portions still further stiffen the nut lock in addition to the resistance afforded by the curved portions 1, 2. Moreover, during the 10 process of clamping this form of my improved nut lock, the latter will seat against the clamping surface at the points 1, 3, and 4, on one face of the nut lock, and at the points 2, 5, and 6, on the other face of the nut lock, thus affording three points of support against the clamping surfaces, thereby 15 rendering the position of the nut lock exceedingly stable and firm during the final process of clamping.

In carrying out my invention the demands 20 of the occasion govern the degree to which the nut lock should be stiffened so as to afford a certain resistance to the action of the clamping elements.

I do not wish to be limited to any particular number of lateral gradual curvatures in the nut lock out of the line of the spiral, nor do I wish to be limited to the 25 location of such curvatures so long as the latter comprise transverse portions including the side faces and the edges and extend 30 laterally outside the line of the spiral to

form concavo-convex compressible spring portions, since such number and location of these curvatures merely vary the resistance of the nut lock to the clamping elements.

35

Having thus described my invention what I claim as new and desire to secure by Letters Patent is:—

1. A nut lock, consisting of a segment of a spiral coil having transverse portions, including the side faces and the edges and located remote from its ends, curved laterally into concavo-convex compressible spring portions of gradual curvature which extend 40 out of the line of said spiral.

2. A nut lock, consisting of a segment of a spiral coil whose transverse extremities including the side faces and the edges are each gradually curved laterally out of the line of the spiral, a transverse part of said 45 segment also including the side faces and the edges intermediate said extremities being also curved laterally out of the line of the spiral, said curved parts all forming concavo-convex compressible spring portions of 50 gradual curvature.

In testimony whereof I affix my signature in presence of two witnesses.

CYRUS H. LOUTREL.
